UNITED STATES PATENT OFFICE.

NATHAN U. WALKER, OF WELLSVILLE, OHIO.

CHIMNEY-BONNET AND WIND-GUARD.

SPECIFICATION forming part of Letters Patent No. 233,584, dated October 19, 1880.

Application filed September 3, 1880. (No model.)

To all whom it may concern:

Be it known that I, NATHAN U. WALKER, of Wellsville, in the county of Columbiana and State of Ohio, have invented a new and useful Improvement in Chimney - Bonnets and Wind-Guards; and I do hereby declare the following to be a full, clear, and exact description thereof, reference being had to the accompanying drawings, forming a part of this specification, in which—

Figure 1 is a vertical section of two of my improved ventilating chimney-bonnets, illustrating their position while being burned. Fig. 2 is a side elevation of a chimney-bonnet with a movable wind-guard, and Fig. 3 is a similar view of a chimney-bonnet with a fixed wind-guard.

Like letters of reference indicate like parts in each.

To enable others skilled in the art to make and use my invention, I will now describe its construction and manner of use.

I form the bonnet *a* of plastic material in the usual way of making such articles, but with a seat or shoulder, *b*, at the upper end, and with a wind-guard, *c*, which is either fixed or movable. In case the wind-guard is fixed the seat *b* extends around outside of it, as shown in the lower part of Fig. 1 and by Fig.

3. In case the wind-guard is movable it rests

upon the seat *b* when in place, as shown in the upper part of Fig. 1 and in Fig. 2. The function of the seat *b*, besides furnishing a seat for the movable wind-guard, is to enable the bonnets *a* to be piled one upon the other in the kiln, and so economize room therein, and thereby save fuel, time, and labor in the burning operation. This is a large saving, as heretofore such articles had to be burned separately. The wind-guard *c*, being closed at the top, prevents the wind from blowing or puffing down the chimney, while the openings *c'* always create a draft in the tube *a* and prevent its clogging and choking up with soot. It also adds to the beauty of the chimney.

What I claim as my invention, and desire to secure by Letters Patent, is—

1. A chimney-bonnet provided with a seat or shoulder at its upper end, substantially as and for the purposes described.

2. A chimney-bonnet having a ventilating wind-guard closed at the top and provided with openings in its sides, substantially as and for the purposes described.

In testimony whereof I have hereunto set my hand.

NATHAN U. WALKER.
